OUTDOOR LIGHTING FIXTURE OR SIMILAR ARTICLE

Philip J. Mole, Elmwood Park, Ill.

Application March 25, 1959, Serial No. 55,165

Term of patent 14 years

(Cl. D48—31)

Figure 1 is an elevational view of an outdoor lighting fixture, or a similar article, showing my new design;

Figure 2 is a top plan view of the lighting fixture of Figure 1;

Figure 3 is a bottom plan view of the lighting fixture of Figure 1; and

Figure 4 is a view taken on the plane of line IV—IV of Figure 1, but with some of the utilitarian parts of the fixture removed.

I claim:

The ornamental design for an outdoor lighting fixture or similar article, substantially as shown.
